[57] **CLAIM**

The ornamental design for a combined bottle and cap, substantially as shown and described.

DESCRIPTION

FIG. 1 is a left side elevational view of a combined bottle and cap showing my new design, the right side being substantially a mirror image thereof;

FIG. 2 is a rear elevational view thereof;

FIG. 3 is a front elevational view thereof;

FIG. 4 is a top plan view thereof; and

FIG. 5 is a bottom plan view thereof.

*Fig. 1**Fig. 2*
